UNITED STATES PATENT OFFICE

147,733

DESIGN FOR A SPOTLIGHT OR SIMILAR ARTICLE

William A. Mendelsohn, Dayton, Ohio, assignor to Jandor, Incorporated, Dayton, Ohio, a corporation of Ohio

Application August 23, 1946, Serial No. 132,779

Term of patent 14 years

(Cl. D48—20)

To all whom it may concern:

Be it known that I, William A. Mendelsohn, a citizen of the United States, residing at Dayton, in the county of Montgomery and State of Ohio, have invented a new, original, and ornamental Design for a Spotlight or Similar Article, of which the following is a specification, reference being had to the accompanying drawing, forming a part thereof.

Figure 1 is a side elevational view of a spotlight showing my new design.

Fig. 2 is a similar view at right angles to Figure 1.

Fig. 3 is a top plan view.

The dominant features of the design reside in the portion shown in full lines in the drawing.

I claim:

The ornamental design for a spot light or similar article, substantially as shown and described.

WILLIAM A. MENDELSON.
